(57) **CLAIM**

We claim the ornamental design for a faucet, as shown and described.

DESCRIPTION

FIG. 1 is a front left perspective view of an embodiment of the claimed design;

FIG. 2 is a rear left perspective view of the claimed design of FIG. 1;

FIG. 3 is a front right perspective view of the claimed design of FIG. 1;

FIG. 4 is a top view of the claimed design of FIG. 1;

FIG. 5 is a front view of the claimed design of FIG. 1;

FIG. 6 is a rear view of the claimed design of FIG. 1;

FIG. 7 is a left side view of the claimed design of FIG. 1; and,

FIG. 8 is a right side view of the claimed design of FIG. 1. The ornamental design which is claimed is shown in solid lines in the drawings. The broken lines in the drawings are for illustrative purposes only and form no part of the claimed design. Broken lines formed by equal length dashes show unclaimed portions of the design. Broken lines formed of unequal length dashes (i.e., dash-dot) show boundaries between claimed and unclaimed portions of the design.

While the accompanying drawings illustrate one or more exemplary embodiments, it should be understood that according to other exemplary embodiments that should be considered to be within the possession of the inventors of the present application at the time this application is being filed, it is contemplated that any illustrated solid lines (or portions thereof) may be converted to broken lines and that any illustrated broken lines (or portions thereof) may be converted to solid lines so as to claim or disclaim portions, components, or sub-components of the designs shown. It is further contemplated that shading may be added or removed to claim or disclaim the corresponding surfaces.
